DIAPHRAGM SIDE CURTAIN

Leonard R. Schuster, San Francisco, and Otto B. Schoenky, Los Angeles, Calif.

Application October 29, 1945, Serial No. 625,124

8 Claims. (Cl. 160—23)

1

The present invention relates to diaphragm curtains for closing the spaces between the ends of coupled or articulated railway cars.

The principal object of the invention is to provide a construction in which the flexible curtains can be made of inelastic material, such as coated or uncoated woven textile material, thereby eliminating the use of rubber, which is presently scarce and is unsatisfactory because of its short life.

Another object of the invention is to provide resilient mountings for the curtains, which expand and contract under relative movement between the cars, as when proceeding on curved track, without placing undue strain on the curtains themselves.

Another object is to provide spring rollers on which the curtains are wound, and to provide mountings for said rollers which permit them to turn with a minimum of friction and which exclude dust, rain and snow.

Still further objects and advantages of the invention will become apparent from the following description, which should be read with the understanding that the form, construction and arrangement of the several parts may be changed without departing from the spirit of the invention as defined in the claims.

In the accompanying drawings:

Fig. 1 is a partly broken side elevation of the ends of adjacent articulated cars.

Fig. 2 is a section on the line 2—2 of Fig. 1.

Fig. 3 is a horizontal section, enlarged, of the roller and its housing shown in Figs. 1 and 2.

Fig. 4 is a vertical section of the roller showing its bearings and internal spring construction.

Referring for the moment to Figs. 1 and 2, the complete diaphragm comprises three separate curtains made of flexible inelastic material such as duck or canvas, which may be coated or suitably waterproofed if desired. There is a roof curtain 21 and two side curtains 22, one at each side of the cars 23. The side curtains are identical, only one being shown and described herein.

In the construction shown in Figs. 1 and 2, both ends of the side curtain 22 are attached to and wound upon spring operated rollers 24 mounted in bearings secured to the ends of the cars at their corners. The center of the curtain is attached to a vertical bar 25 which has angle brackets 26 secured to its inner face. Pivot links 27 and 28 connect the brackets 26 of the bar 25 with angle brackets 29 secured to the end plates or structures 30 of the cars. The bar 25 and the central portion of the curtain are thus

2

held in vertical position midway between the ends of the cars. For additional strength and to prevent sagging, the upper pivoted links 28 are made double, as shown in Fig. 1, there being one pair of horizontal links 28 and a pair of inclined bracing links 28a, the pivots of both pairs of links being vertically aligned.

As the side corners of the cars move toward or away from each other on curved track, the ends 10 of the curtain 22 are taken up or paid out by the spring rollers 24. There will be a small amount of in and out movement at the center of the curtain, caused by the angularity of the links 27 and 28, but this is of no consequence and is also taken 15 care of by the rollers 24.

Each roller is constructed and mounted as shown in Fig. 4. It comprises a cylindrical tubular body 31 having heads 32 secured to its ends and mounted in ball bearings 33, whose outer 20 races are seated in cups 34 carried by angle brackets 35 secured to the end plate 30 and corner post 36 of the car. The upper head 32 has a central aperture through which extends a spindle 37 whose upper end 38 is squared or flattened and 25 seats within a similarly shaped aperture in the bracket 35. The spindle is thereby held stationary. An intermediate head 39 is secured within the roller and has a step bearing 40 in which the lower end of the spindle is rotatably mounted. A helical spring 41 surrounds the spindle within the roller, the upper end of said spring being fastened 30 to the spindle and the lower end being fastened to the intermediate head 39. A few coils of the spring 41 at its upper end are wound tight around the spindle 37, as shown at 42, to distribute the stress set up at the point of rigid attachment 43 between spring and spindle, and thus minimize breakage and promote long life. The aperture through the upper head 32 is considerably larger than the spindle 37, so that there is no friction 35 at that point. The roller is therefore exceptionally free running, there being only the two end ball bearings 33 and the intermediate bearing 40 of the spindle 37. The curtain (not shown in Fig. 4) is attached to the roller in any conventional manner.

Each roller 24 is enclosed in a housing to exclude dust, rain and snow, as shown in Fig. 3. One side of the housing is formed by a strip 44 secured to the end plate 30 and corner post 36 of the car. Two sides of said housing are formed by a bent plate or flap 45 hinged at 46 to the fixed strip 44 and held in closed position by a spring 47. The outer edge of the hinged flap 45 45 is rolled as shown at 48, and bears lightly against

the curtain 22. The outer side of the housing is formed by a flat strip or flap 49 having a slightly out-turned forward edge 50, which is secured by a hinge 51 to the side plate 52 and corner post 36 of the car. The hinge 51 is provided with a spring of conventional type indicated at 53 which presses the flap 49 lightly against the curtain 22 wound upon the roller. The housing is thus sealed by contact with both inner and outer surfaces of the curtain, but can be easily opened to permit cleaning or removal and replacement of the roller. The bearing cups 34 are removably secured to the brackets 35 in any suitable manner, not shown.

We claim:

1. A diaphragm curtain for articulated railway cars comprising a sheet of flexible material extending between adjacent cars approximately flush with a side wall thereof, a vertical roller mounted at a corner of each car, the ends of said curtain respectively being connected to and wound upon said rollers, a spring within each roller acting to rotate the same to wind said curtain thereon, a substantially vertical bar secured to said curtain between said rollers, and pivotally mounted links connecting said bar with the ends of the cars, said bar and the central portion of the curtain being supported and maintained in substantially vertical position by said links.

2. A diaphragm curtain for articulated railway cars comprising a sheet of flexible material extending between adjacent cars approximately flush with a side wall thereof, a vertical roller mounted at a corner of each car, the ends of said curtain respectively being connected to and wound upon said rollers, a spring within each roller acting to rotate the same to wind said curtain thereon, and a pair of angularly related links having their inner ends pivotally connected to the ends of the respective cars and their outer ends pivotally connected together midway between said cars, a portion of said curtain between its ends being connected to and supported by the outer ends of said links.

3. A diaphragm curtain for articulated railway cars comprising a sheet of flexible material extending between adjacent cars approximately flush with a side wall thereof, a vertical roller mounted at a corner of each car, the ends of said curtain respectively being connected to and wound upon said rollers, a spring within each roller acting to rotate the same to wind said curtain thereon, a substantially vertical bar secured to said curtain between said rollers, two vertically spaced pairs of movable angularly related links for supporting said bar and the central portion of said curtain, the outer ends of each pair of links being pivotally connected to said bar, and the inner ends of said links being respectively pivotally connected to the ends of the cars.

4. A diaphragm curtain for articulated railway cars comprising a sheet of flexible material extending between adjacent cars approximately flush with a side wall thereof, a vertical roller mounted at a corner of each car, the ends of said curtain respectively being connected to and wound upon said rollers, a spring within each roller acting to rotate the same to wind said curtain thereon, a housing surrounding each of said rollers, each housing having two portions of its walls formed by hinged flaps, the free edge of one flap bearing against the inside surface of the curtain and the free edge of the other flap bearing against the outside surface of said curtain, and springs for maintaining said flaps in position

with their free edges in contact with said curtain.

5. In diaphragm curtain construction for railway cars having a sheet of flexible material extending between the ends of adjacent cars substantially in the plane of a side wall thereof, means for attaching at least one end of said curtain to the corner of one car comprising a spring roller mounted vertically adjacent the corner of the car, a housing surrounding said roller, said housing comprising a fixed portion secured to a corner of the car, an inner movable wall hinged to said fixed portion and covering the inside of said roller, the free edge of said inner movable wall contacting the inside of the curtain, an outer movable wall hinged to said corner of the car and extending substantially in the plane of the associated side thereof, the free edge of said outer wall contacting the outside of the curtain, and springs acting on said movable walls to maintain their free edges in contact with said curtain.

6. A diaphragm curtain for railway cars comprising a sheet of flexible material extending between the ends of adjacent cars substantially in the plane of a side wall thereof, a spring roller mounted vertically adjacent a corner of each car, the respective ends of said curtain being secured to and wound upon said rollers, upper and lower brackets secured to each car near its corner, ball bearings mounted in said brackets, the ends of said rollers being mounted in said ball bearings, a housing surrounding each roller and the associated bearings, portions of the walls of said housing being formed by two hinged flaps, the free edges of said flaps contacting respectively the inner and outer surfaces of the curtain, and springs acting on said flaps to maintain their free edges in contact with said curtain.

7. A diaphragm curtain for railway cars comprising a sheet of flexible material extending between the ends of adjacent cars substantially in the plane of a side wall thereof, a roller mounted vertically adjacent the corner of each car, the ends of said curtain respectively being secured to and wound upon said rollers, each roller having a cylindrical shell, a head at each end of said shell, one of said heads having an axial aperture, brackets secured to the car near a corner thereof in which said heads are rotatably mounted, an intermediate head within said shell, a spindle within said shell, one end of said spindle being rotatably mounted in said intermediate head and the other end of said spindle extending freely through said aperture head without contact therewith and having non-rotatable engagement with the bracket adjacent thereto, a helical spring surrounding said spindle within said shell, one end of said spring being fixed to said spindle and the other end of said spring being fixed to one of said heads, and a housing surrounding said roller, portions of the walls of said housing being formed by two hinged flaps, the free edges of said flaps contacting respectively the inner and outer surfaces of the curtain, and springs acting on said flaps to maintain their free edges in contact with said curtain.

8. In diaphragm curtain construction for railway cars having a sheet of flexible material extending between the ends of adjacent cars substantially in the plane of a side wall thereof, means for attaching at least one end of said curtain to a corner of one car comprising a roller mounted vertically adjacent said corner of the car, said roller having a cylindrical shell, a head at each end of said shell, one of said heads having an axial aperture, brackets secured to the

car near said corner in which said heads are rotatably mounted, an intermediate head within said shell, a spindle within said shell, one end of said spindle being rotatably mounted in said intermediate head and the other end of said spindle extending freely through said apertured head without contact therewith and having non-rotatable engagement with the bracket adjacent thereto, a helical spring surrounding said spindle within said shell, one end of said spring being fixed to said spindle and the other end of said spring being fixed to one of said heads, and a housing surrounding said roller, portions of the walls of said housing being formed by two hinged flaps, the free edges of said flaps contacting respectively the inner and outer surfaces of the curtain, and springs acting on said flaps to maintain their free edges in contact with said curtain.
